UNITED STATES PATENT OFFICE.

FREDERICK HERBERT WILLIAM HIGGINS, OF LONDON, ENGLAND.

PRINTING-TELEGRAPH.

SPECIFICATION forming part of Letters Patent No. 398,833, dated March 5, 1889.

Application filed May 29, 1888. Serial No. 275,424. (No model.) Patented in England February 10, 1887, No. 2,128.

To all whom it may concern:

Be it known that I, FREDERICK HERBERT WILLIAM HIGGINS, electrical engineer, a subject of the Queen of Great Britain, residing at 5 17 Cornhill, in the city of London, England, have invented certain new and useful Improvements in Electrical Type-Writers, (for which I have obtained Letters Patent in Great Britain, No. 2,128, dated February 10, 1887,) 10 of which the following is a specification.

The leading features of the improved electrical type-writer are the following: A manipulator and a printer connected by two electric circuits with automatic apparatus in the manipulator for continuously opening and closing a circuit and keeping in rotation a type-wheel in the printer. Finger-keys in the manipulator depressed by the operator stop this automatic apparatus and also the type-wheel 15 whenever the latter arrives in position for printing. The same finger-keys close the printing-circuit and bring the printing mechanism into use. The matter thus transmitted is printed upon a page line by line. An indicator in the manipulator shows, for the information of the operator, the number of letters struck in any line being printed. By the manipulation of a finger-key the index of this indicator is returned to the starting-point and 20 the apparatus brought into position to print a new line. This is accomplished by the transmission of a printing-current when the shaft of the type-wheel is in a given position, corresponding with a blank upon the type-wheel, 25 and the operation of the printing mechanism at this time moves the paper forward for the next line to be printed upon it.

In the accompanying drawings I have shown my invention embodied in one practical and 30 efficient manner.

Figure 1 is an elevation of the manipulator. Fig. 2 is a plan of the same. Fig. 3 is a plan with the cover and some of the parts removed. Fig. 4 is a section on the line 4 4 in Fig. 3, 45 omitting some of the parts. Fig. 5 is a section on the line 5 5 in Fig. 3, omitting some of the parts. Fig. 6 is a detail of the cam-circuit-interrupting wheel. Fig. 7 is a plan of the printer, omitting some of the parts. Fig. 50 8 is an end elevation. Fig. 9 is a back view of the printing lever and magnet. Fig. 10 is an elevation showing separately that por-

tion of the apparatus for returning the type-wheel to zero and feeding the paper. Fig. 11 is an elevation of the type-wheel with its inking-roller. Fig. 12 shows in plan, on a larger scale, parts of the apparatus shown by Fig. 10. Fig. 13 shows the type-wheel circuit. Fig. 14 shows the printing-circuit. Figs. 15 and 16 are diagram detail views showing the checking of the printing-frame to prevent printing both in the zero and spacing positions of the type-wheel. Figs. 17 and 18 are perspective views of the printing-frame and devices for operating the paper-roller and the type-wheel 65 feeding mechanism.

What I term the "manipulator" consists, generally, of an apparatus having an automatic circuit-interrupter, in the interrupted circuit of which is included a magnet for rotating the type-wheel step by step to bring the desired letter into proper position with reference to the rotary movement of the wheel for printing. In the manipulator there are the desired number of keys, either of which, when depressed, checks the automatic circuit-interrupter, and consequently the rotation of the type-wheel. Upon such depression of the key and pause of the type-wheel the printing-circuit, including the printing-magnet, is completed, and the printing-frame or paper-carrying devices are thereupon moved up to the type-wheel. Upon the retrograde movement of the printing-frame the type-wheel is moved laterally upon its shaft or spindle the space 85 of one letter to bring it into position to print the next letter in the line. Each time that the printing-circuit is completed a magnet in the printing-circuit is energized, and an indicator for keeping a visual record of the number of letters struck in the line then being printed is operated.

With this general statement, I will now describe the construction and operation of the various parts of the apparatus.

In Figs. 1 to 6, which illustrate the manipulator, *a* is the propelling-magnet, whose circuit is automatically interrupted, as presently described, and by which the finger *g* is rotated step by step beneath the circular series of 100 keys *h*, by any one of which, when depressed, it may be checked. The type-wheel-actuating magnet *B*, Fig. 13, being in the same circuit with the magnet *a*, as above mentioned,

the type-wheel will move step by step in unison with the finger g . The armature b of the magnet a is fixed to a pivoted propelling-lever, c , which operates the ratchet-wheel d' on the shaft d . The end of the lever c is bifurcated and embraces the ratchet-wheel, and when the lever is attracted by the magnet one of its bifurcations operates by means of its beveled end against a tooth of the ratchet-wheel and moves the wheel through a space of half a tooth, and when the armature is retracted by its spring d^x the other bifurcation of the lever, acting against the opposite side of the ratchet-wheel, moves it through another like space, and thus as the circuit is alternately opened and closed the ratchet-wheel and its shaft are constantly rotated step by step. A retaining-pawl, a^4 , engages a duplicate ratchet-wheel, d^2 , on the same shaft, d , and prevents slack motion. On the same shaft is the circuit-interrupting cam-wheel for operating the circuit-completing lever e . A second lever, e^x , is also shown; but this is only used when the manipulator is required to work printers in two circuits. The lever e vibrates upon an insulated fulcrum, e' , and carries a contact-spring, e^2 , which works against an insulated contact-screw, f . When a notch in the cam-wheel comes under the jaw or lug on the lever e , the lever is by its ordinary retractile spring drawn away from the contact-screw f and the circuit is opened. The magnet a , now being demagnetized, releases its armature, and its lever c is drawn back by its retractile spring, the effect of which is, that one arm of its bifurcated end acts on the ratchet d' , moving it and the cam-wheel d^3 , and a tooth of the cam-wheel lifts the contact-lever e and re-establishes contact at f , whereupon the armature-lever c is drawn up by its magnet, and the ratchet-wheel d' is acted upon by the other fork of the lever, and moves the spindle and cam-wheel so that a notch therein again comes under the end of the lever e , and the operation is repeated. The propelling-circuit (shown by Fig. 13) is therefore automatically opened and closed, and the shaft d , carrying the pointer g , is rotated step by step and in unison therewith. The type-wheel in the printer is correspondingly moved, as presently described, because the type-wheel-actuating magnet B is included in the interrupted circuit. The finger g , carried by the shaft d , is insulated therefrom by a block of vulcanite, g' . The finger-keys h are arranged in a circle around the frame of the manipulator, and are held raised by springs h' . When any finger-key is depressed, the finger g comes against it, as shown in Fig. 14, the cam-wheel d^3 is checked, and of course the type-wheel in the printer is simultaneously stopped in a position corresponding with the particular key depressed. The contact of the finger g with the key also completes the printing-circuit, (see Fig. 14,) which circuit includes the print-magnet H , and the printing-frame is actuated, as pres-

ently described. The printing-circuit also includes a magnet, i , located in the manipulator, Figs. 3 and 14, which magnet, as presently described, serves to operate an indicator each time that the printing-circuit is closed, so that the operator may know at a glance how many keys have been depressed or letters have been struck in the line then being printed. When a new line is started, the indicator is returned to zero, as described below.

Figs. 7 to 12 illustrate the printer. A is the frame of the machine, and B the type-wheel-actuating magnet, whose armature is carried by arms c , projecting from a rock-shaft, C. This shaft carries the type-wheel propelling-lever C' , Figs. 7 and 8, which is bifurcated at its end, or carries a propelling-anchor, C^2 , which engages the teeth of a ratchet-wheel, c' , on the type-wheel shaft D, as usual. The type-wheel E slides along this shaft, being moved as presently described, but is prevented from turning thereon by two rods, $D' D'$, passing through it parallel with the shaft D, and carried by arms c^2 , projecting from said shaft. By the rotation of the shaft D and type-wheel the proper letters thereon are in succession and in correspondence with the movement of the finger g in the manipulator brought into the printing position. Parallel with the type-wheel shaft D is a screw-rod, F, which, as the printing progresses, effects the movement of the type-wheel step by step along its shaft in the following manner: A nut, F' , on the screw-rod has a laterally-projecting fork, F^2 , which embraces the type-wheel. The nut is guided and prevented from turning by two arms, F^3 , depending from it and terminating in small rollers which bear on either side of a fixed bar, F^4 , Fig. 11, mounted in the frame. Vertical standards F^4 , carried by the nut F' , have laterally-projecting arms f' pivoted thereon, and these arms carry the inking-roller G. Obviously, now, if the screw-rod be rotated, the nut F' , type-wheel, and inking-roller will move together laterally without reference to their rotation. A partial rotation is given the screw-rod and the type-wheel advanced laterally into position to print a new letter after each action of the printing-frame K, as I will now describe. The armature H' of the print-magnet is carried by arms $I' I'$, projecting from a rock-shaft, I, which shaft also carries the printing-lever frame K K. The sheet of paper V passes, as shown in Fig. 8, between the face of an elastic pad, K' , extending across the frame K, and wires $v v$, also fixed across the frame. When the printing-circuit is closed by the abutment of the finger g in the manipulator against a depressed key, as described, the print-magnet is energized, and, attracting its armature, the printing-frame carrying the paper is moved up to the type-wheel, and an impression is taken therefrom, (except in certain instances presently referred to.) The type-wheel has of course

been rotated by the action of the manipulator to present the proper letter upon its periphery to the paper, and has also been advanced along its shaft to the proper lateral position in the following manner, (see Figs. 10 and 11:) A pin, L^4 , in the side of the printing-frame K engages a slot, L^5 , in a lever, L, pivoted at L' , and carrying a pawl, L^2 , which acts upon the ratchet-wheel M on the end of the screw-rod F. When the printing-frame advances, the lever L is lifted and its pawl L^2 slips over the teeth of the ratchet-wheel M; but when the printing-frame is withdrawn by its ordinary retractile spring the pawl engages the ratchet, rotates it one step, and consequently through the action of the screw-rod moves the type-wheel along its shaft into lateral position to print the next letter. A retaining-pawl, N, having a spring, N^x , engages the ratchet-wheel M and prevents its back motion. I provide a type-wheel returner, which is preferably constructed in the following manner: Upon the opposite end of the screw-rod F is a pinion, F^5 , Fig. 7, that gears with a spur-wheel, F^6 , which as the screw-rod is rotated by the pawl L^2 winds up a coiled spring, F^7 . When a line of printing has been completed and the ratchet M is released, as I will now describe, the spring F^7 , acting to rotate the screw-rod in a reverse direction, returns the type-wheel to zero, or the initial position for the commencement of a new line.

On the shaft D of the type-wheel is a radial pin or shifter, D^2 , which once in each revolution of the type-wheel operates against a vertical incline, O^2 , upon a horizontally-swinging piece or yoke, O, Figs. 10 and 12, turning upon a vertical pivot, O' . The pin moves the end O^2 of the yoke O (against the pressure of a light spring, O^4) toward the adjacent end of the instrument, or toward the observer, looking at Fig. 10, while the opposite end, O^3 , moves inward. A lever, P, jointed at its upper end, p, to the printing-frame K, has its lower end connected by a horizontal pivotal link, Q, with the tail or right-angular extension N' of the retaining-pawl N. A tail or depending projection from the pawl L^2 lies against a pin, Q' , in the horizontal link Q.

Ordinarily the to-and-fro movement of the printing-frame does not influence the pawls; but when the pin D^2 on the axis D once in each revolution comes to the position in which it is shown in Fig. 10 and displaces the piece O, as just described, then, if at this moment the printing-frame K is swung by the depression of the zero-key h^x , Fig. 5, it brings the lever P into contact with the end O^3 of the piece O, and, the end O^3 then forming a fulcrum about which the lever P turns, the lever moves the link Q to the right, thereby lifting both the pawls L^2 and N away from the teeth of the ratchet, and the spring F^7 returns the type-wheel to its starting-point. The type-wheel may therefore be returned to the zero position at any point in the line, as well as at

the end of the line, merely by depressing the zero-key.

D^3 D^4 are pins on the shaft D, which prevent the printing-lever advancing sufficiently to bring the paper into contact with the type-wheel when the releasing operation just described takes place. These pins also stop the advance of the printing-frame, to prevent printing when the type-wheel is at the zero position.

The sheet of paper V is laid in the manner indicated in Fig. 8 up from the printing-pad K' over a metallic roller, R, against which the propelling or paper-driving pawls S (seen in Fig. 10) work. Above the propelling-pawls S are retaining-pawls T T, Fig. 8, which serve simply to prevent the paper being drawn back when the propelling-pawls S retire. The propelling-pawls S, beneath which the paper passes, are carried by levers S', which are movable about the shaft of the roller R. One of the levers S' has upon it an arm, S^2 , from which the roller receives movement at the proper time for feeding the paper forward—that is to say, when the type-wheel is released and allowed to go back to the commencement of a line. At this time the pin K² upon the printing-frame strikes against a filling-piece or pusher, U, and this in turn abuts against the arm S^2 of the lever carrying the pawls S, so that when the printing-frame advances it moves the arm and the pawls S, and so it rotates the roller one step, carrying forward the paper, which is held between the roller and the pawl. Springs s hold the pawls S in contact with the paper. This filling-piece or pusher U is jointed to the printing-frame by means of the horizontal pivot or pin U', which permits movement of pusher U in a plane parallel with that in which the printing-frame moves; but the pusher U also has a movement at right angles thereto on the pivot-pin u, which unites it with the pin U'.

U^2 is an arm projecting out from the rear of the pusher or filling-piece U, and this arm is embraced by a fork, O^5 , fixed to the piece O, so that when the piece O is moved by the pin D^2 on the shaft D to liberate the type-wheel, as already described; it also places the filling-piece or pusher U between the pin K² and the arm S^2 , and consequently the pawl by which the paper is fed forward receives the movement required when the printing-frame advances.

In Fig. 13, which indicates the arrangement of the propelling-circuit, the course of the current may be traced in the manipulator from the battery X through the propelling-magnet a, the screw f, a spring, e^2 , and lever e, thence to the printer and through the coils of the type-wheel magnet B, and so back to the battery.

In Fig. 14, which indicates the arrangement of the printing-circuit, the course of the current may be traced in the manipulator from the battery X through the electro-magnet i

of the indicator, the finger g , and one of the finger-keys h to the frame of the manipulator, thence by a wire to the printing-magnet H , and by another wire back to the battery.

5 As above mentioned, in order that the operator may be informed how many letters have been printed in any line, I employ the following arrangement: The magnet i in the printing-circuit operates a propellent-lever, k , Figs. 3 and 5, which drives a ratchet-wheel, l' , fast on the shaft l . A ratchet, l'' , fast on the same shaft receives a check-pawl, l''' , which prevents false movements. A disk, l'' , fast on the shaft l , is perforated around its 10 edge for the reception of a pin, m^5 , on a corresponding disk, m' , carried by a sleeve, m , loosely mounted on the reduced upper end of the shaft l . A spring, m^2 , surrounds the shaft l within said sleeve, and normally holds the 15 disks l'' and m' in contact. A finger, m^3 , on the upper end of the sleeve indicates upon any suitable dial the number of times the print-magnet circuit has been closed. When a line is finished, however, and the zero-key h^x is 20 depressed, a collar, h^4 , thereon moves the finger n around its pivot n' and forces the finger against the incline or spiral cam m^x on the sleeve m , thereby lifting the sleeve, disengaging the disks m' and l'' , and turning the 25 sleeve to bring its index-finger m^4 to zero. On the release of the zero-key the spring within the sleeve returns it and brings the disks m' and l'' again into engagement.

From the above description the operation 30 of various parts will be obvious, and since the arrangement of circuits and the location of the actuating-magnets therein are fully shown in Figs. 13 and 14, further description of the operation seems unnecessary. It may be re- 35 marked, however, that the apparatus is brought to unison each time that the type-wheel is returned to the initial or zero position.

In order to allow of spaces being left between successive words, it is necessary to be able to prevent the paper from coming into contact with the type-wheel when the printing-lever is swung upon the depression of the spacing-key. For this purpose the pins D^3 40 on the axis of the type-wheel are bent slightly downward, so that when the type-wheel armature is attracted and held by its magnet the first time after the type-wheel has passed zero the pin upon the printing-lever comes 45 against the bent end of the pin on the axis of the wheel and is stopped by it. Again, when the type-wheel is at zero and the printing-lever is swung, the paper is similarly prevented from touching the type-wheel by reason 50 of the pin on the printing-lever coming against the stop. A pin may also be provided at the other end of the axis of the type-wheel, to effect or assist in effecting the same purpose. In this case sufficient breadth is 55 given to the end of the pin to enable it to get in the way of a pin on the printing-lever

when the type-wheel stands either at zero or half a step in advance of zero.

The mechanism above described can readily be adapted to that class of instruments which are driven by a weight or spring.

I claim as my invention—

1. The combination, substantially as hereinbefore set forth, of the rotating finger g , the type-wheel, electro-magnetic devices for actuating the rotating finger and the type-wheel step by step and in unison, a single electric circuit including the electro-magnetic devices for actuating the rotating finger and the type-wheel, a circuit-breaker in said circuit, the finger-keys, the print-frame, its electro-magnetic actuating devices, and a second electric circuit including the finger-keys, the rotating finger g , and the print-frame-actuating devices.

2. The combination, substantially as hereinbefore set forth, of the rotating finger g , the shaft on which it is mounted, the notched wheel carried by said shaft, but insulated from the finger g , the circuit making and breaking lever engaging with said notched wheel, the propellent-lever, the ratchet on the shaft of the finger g , with which the propellent-lever engages, its electro-magnet, the type-wheel, its electro-magnetic actuating devices, and an electric circuit including the type-wheel-actuating devices, and the electro-magnet which actuates the propellent-lever.

3. The combination, substantially as hereinbefore set forth, of the type-wheel, the shaft on which it is mounted and on which it is free to slide, electro-magnetic devices for revolving the type-wheel, the screw-shaft, the print-frame, connections between the print-frame and the screw-shaft, whereby the screw-shaft is revolved to advance the type-wheel on its shaft, the coiled spring, gearing between the spring and screw-shaft, the shifting-pin D^2 on the type-wheel shaft, and connections between the pin and the screw-shaft, whereby the movement of the print-frame at a predetermined position of the pin D^2 is caused to automatically release the screw-shaft to allow its reverse movement by the spring with which it is geared.

4. The combination, substantially as hereinbefore set forth, of the type-wheel, the shaft on which it is mounted and with which it revolves, electro-magnetic devices for revolving the shaft, the screw-shaft connected with the type-wheel for moving it back and forth on its shaft, the print-frame, connections between the print-frame and the screw-shaft for revolving it, the rotating finger of the transmitter, the finger-keys engaging therewith, an electric circuit including the finger-keys, rotating finger, and the print-frame-actuating devices, one of said keys being arranged to actuate the print-frame to release the connections between the print-frame and the screw-shaft when the finger is depressed.

5. The combination, substantially as here-

inbefore set forth, of the type-wheel, the type-wheel shaft on which the type-wheel is free to slide, the screw-shaft, the nut on the screw-shaft, connections between the nut and the 5 type-wheel, the coiled spring, gearing between the coiled spring and the screw-shaft, the oscillating printing-frame, the toothed wheel on the end of the screw-shaft, the pawl engaging with the toothed wheel, a lever, on one end of 10 which said pawl is mounted and having its opposite end connected to the printing-frame, the retaining-pawl M, the jointed levers connecting said pawl to the printing-frame, the pin D² on the type-wheel shaft, and the pivoted arm O², with which said pin engages to 15 release the pawls from the type-wheel, for the purpose specified.

6. In an electric type-writer, the combination of parts constituting the indicator and 20 by which the indicator is brought to zero, consisting in the combination of the magnet i, lever k, shaft l, and wheel l', disk l'', sleeve m, and disk m', engaging with l'', key h^x, finger n, cam m^x, and pointer m^a.

25 7. In an electric type-writer, the combination of parts for bringing back the type-wheel to the commencement of a line, consisting in the combination of the type-wheel, the shaft on which it is mounted, a pin, D², on the shaft, 30 the piece O, moved thereby, the printing-frame K, the lever P, connected therewith, the retaining-pawls L² and N, also connected with the lever P, the screw F, the nut F', the spring F', and the connecting-gear.

35 8. In an electric type-writer, the combination of parts for advancing the paper at the end of each line, consisting in the combination of the type-wheel, the driving-shaft on which it is mounted, the pin D² on the driving-shaft, the piece O, moved thereby, the filling-piece U, the piece O, connected with the filling-piece U, the pin K² on the printing-frame, the arm S², the paper-driving pawl, and the lever on which said pawl is carried and 40 which carries the arm S².

45 9. In an electric type-writer, the combina-

tion, substantially as hereinbefore set forth, of the type-wheel, the print-frame, the magnet for operating the print-frame, the screw-shaft, connections between the screw-shaft and the 50 type-wheel, the pawls engaging with the screw-shaft, the levers connecting the pawls with the print-frame, the pivoted arm O², the pin D² on the type-wheel shaft engaging at times with the arm O², and the springs for returning the 55 type-wheel to zero.

10. In an electric type-writer, the combination, substantially as hereinbefore set forth, of the type-wheel, the print-frame, the magnet for operating the print-frame, the screw-shaft, connections between the screw-shaft and the type-wheel, the pawls engaging with the screw-shaft, the levers connecting the pawls with the print-frame, the pivoted arm O², the pin D² on the type-wheel shaft 60 engaging at times with the arm O², the spring for returning the type-wheel to zero, the pusher U, the paper-roll, the pawl for operating the paper-roll connected with the pusher U, and connections between the pusher and 65 the pivoted arm O², whereby the pusher is disconnected from the paper-roll-actuating pawl.

11. The combination, substantially as hereinbefore set forth, of the rotating finger, the 75 type-wheel, electro-magnetic devices for rotating the finger and actuating the type-wheel, the printing-frame, the finger-keys, electro-magnetic devices for actuating the printing-frame, and an electric circuit including said actuating devices and the finger-keys, the indicator included in the printing-circuit and actuated step by step in correspondence with each actuation of the printing-frame, and connections between one of the finger-keys and the indicator for returning it to zero. 80 85
